[57] CLAIM

The ornamental design for a video communication unit, as shown.

DESCRIPTION

FIG. 1 is a front perspective view of a video communication unit showing my new design;

FIG. 2 is a top plan view thereof;

FIG. 3 is a side elevational view thereof;

FIG. 4 is an opposite side elevational view thereof;

FIG. 5 is an elevational view of one end thereof;

FIG. 6 is an elevational view of the opposite end thereof; and,

FIG. 7 is a bottom plan view thereof.

The broken line showings in FIG. 7 are for illustrative purposes only and form no part of the claimed design.
